UNITED STATES PATENT OFFICE.

ADOLPH MONSEN, OF LOGANSPORT, INDIANA.

DESIGN FOR AN ENGINE-FRAME.

54,327.

Specification for Design.

Patented Dec. 23, 1919.

Application filed November 27, 1918. Serial No. 264,461. Term of patent 14 years.

To all whom it may concern:

Be it known that I, ADOLPH MONSEN, a citizen of the United States, residing at Logansport, in the county of Cass and State of Indiana, have invented a new, original, and ornamental Design for Engine-Frames, of which the following is a specification, reference being had to the accompanying drawing, forming part thereof.

Figure 1 is a front elevation of the engine frame.

Fig. 2 is an elevation of the engine frame looking at the right side of the engine.

Fig. 3 is an elevation of the engine frame looking at the left side of the engine.

What I claim is:

The ornamental design for an engine frame, as shown.

ADOLPH MONSEN.
